UNITED STATES PATENT OFFICE.

CECIL ALEXANDER ELLIOTT, OF READING, ENGLAND, ASSIGNOR OF ONE-HALF TO
SAMUEL ELLIOTT AND SONS (READING), LIMITED, OF READING, BERKS, ENGLAND.

REVOLVING DOOR.

Application filed January 5, 1921. Serial No. 435,224.

To all whom it may concern:

Be it known that I, CECIL ALEXANDER ELLIOTT, a subject of the King of Great Britain, residing at Gosbrook Road, Caversham, Reading, in the county of Berks, England, have invented certain new and useful Improvements in or Relating to Revolving Doors, of which the following is a specification.

10 This invention relates to revolving turnstile doors.

The object of the invention is by the adoption of spring hinges of a suitable pattern as the hinges or pivots of the leaves of the central revolving body, where such leaves are made movable, to render the latter so that after they are turned from their normal position to open the doorway they may be automatically returned to close the doorway.

15 It applies to the kind of door, the revolving portion of which is composed of a central screen axially arranged through the centre of the outer casing of the enclosing framework, which screen has wings projecting from the ends, which together with the screen approximately form the letter H in plan, and are known as two-compartment revolving turnstile doors; and further to where it is desirable that the central screen body shall contain a door or doors which open both ways on hinges or pivots.

20 According to my invention, I arrange the central screen doors, so that they are adapted to close automatically by the application of suitable springs or other resilient means to the hinges or pivots on which the central door screen is carried.

25 This automatic construction may also be applied to revolving turnstile doors having radial leaves revolving about a central axis, and where it is desirable that the leaves shall close self-actingly.

Also I may provide, when necessary, 30 means in connection with the spring controlled pivots to prevent the leaves closing violently, and the said means may be in the form of air or oil checks or other suitable device.

35 By means of my invention I obtain a combination of a revolving door and spring swung doors, the latter of which are self-closing.

The accompanying drawings illustrate

structures in accordance with the present invention.

In the drawings:—

Figure 1 is a front elevation of a revolving door.

Figure 2 is a sectional plan through the line A—B of Figure 1, showing curved wings.

Figure 3 is a sectional plan similar to Figure 2, but having flat wings with extensions instead of curved wings as in Fig. 2, Fig. 3 also showing said extensions movably connected as by a hinge, but said extensions may be rigidly connected, as by integral formation with the wing; and either type can be used at one or both sides of the structure.

Figures 4 and 4^a are fragmentary views partially in section of spring bolt and spring catch devices.

Figure 5 is a sectional plan of Figure 4.

Figure 5^a is a sectional plan of Figure 4^a.

Figure 6 is a sectional detail showing the elastic cushioning device provided in the stationary framework to make contact with the edge of the revolving wings.

Figure 7 is a sectional plan showing the wings folded back on the screen and forming a gangway at both sides, the screen being centrally positioned.

Figure 8 is a sectional plan showing the wings folded back on the door or screen and forming a central gangway, the door or screen with folded wings thereon being movable on a stationary guide-way to one side of the door framework.

Figure 9 is a rear elevation of the door showing stop brackets and means for automatic release of the wings.

Figure 10 is a sectional plan showing a modified arrangement of the door or screen and foldable wings.

Figure 11 is an elevation of a key device for operating the cable to effect the automatic release of the wings.

Figure 12 is a further elevation of said key device showing the angular position the key takes up when exerting a "pull" action upon the cable.

Figure 13 is a sectional plan showing said key in position upon the door or screen structure.

Figure 14 is a vertical section of the top of the revolving door casing showing the

mode of door suspension and elastic means for the automatic turning and control of the revolving screens,

Figure 15 is a plan thereof,

5 Fig. 16 is a sectional view showing door frame of two compartment door and wings with adjacent parts partially in section and bracket with catch device in position upon wing attached to central screen frame and 10 showing control cables passing from catch device to opening or hole in central screen frame down which they pass and are operated in the herein described manner.

In carrying the invention into effect the 15 central leaves *a* thereof, see Figure 1, are provided with spring hinges *b* and have pivots *c*. These spring hinges and pivots are shown in enlarged detail in Figures 4 and 4^a and 5 and 5^a of the drawings, in 20 which *b* is the spring hinge device and *c* is a pivot.

The spring hinges comprise a casement *b*¹ attached to the door, within the casement is a central pivot *b*² positively fixed at its 25 lower end *b*³ in a ball bearing device *b*⁴ upon the member *b*⁵. At each side of the central pivot *b*² is a roller *b*⁶, carried by a stud *b*⁷, and adapted, when the door is turned to press against a slidable block *b*⁸ and so tension a spring *b*⁹ attached to the block *b*⁸ at 30 one end and supported by bearers *b*¹¹ in which it is free to slide at both ends.

On turning the central door screen members the springs of the hinges *b* are 35 pressed by the slidable bolts which are operated through the hinge pin by the movement of the door members to compress the springs, which when the door members are released react to return the said members.

40 The central leaves *a* of the door are held in closed position by spring catches or bolts *d*, see Figure 1, and it is necessary to withdraw these catches when using the leaves *a* as spring swung doors in order to allow 45 them to swing freely. The withdrawal is effected by connections between the spring catches *d* and the hand lever *e* positioned on the face or edge of each door.

Further, I arrange, if such is desirable, 50 that the wings *f* attached to the central door frame body *g* shall be hinged or pivoted at *h* in order to adjust them in their relation to the outer circular screen *j* or to allow of their being folded inwards upon the central 55 door body *g*, see Figures 2, 3, 7, 8 and 10, such hinges or pivots, or the movements thereof, being controlled by springs *k*, if desirable, or other resilient means, see Figure 10.

60 In order to ensure that the leaves *f* shall be held in their proper position, brackets *l*, see Figures 2, 3, 7, 8, 9 and 10, are provided attached to the central body frame *g* with means of attachment at their ends to allow 65 for adjustments being made. These brackets

ets *l* hold the wings *f* at right angles to the members *a* against the action of springs *k* and are arranged to be turned out of the way when the leaves *f* are to be folded upon the central door body *g*, and when the leaves 70 are so folded they are held securely by catch plates *m*.

The central body *g* with folded leaves *f* is turnable at right angles to its central axis or line of suspension and when secured in 75 this position by bolts or catches it provides clear gangways *n* on either side, see Figure 7, and direction of arrows on either side.

In order to give as much space as possible 80 in these gangways, it may be desirable to make the wings *f* flat or with slight curvature, as it is obvious that if flat wings *f* are employed, these when folded will provide more gangway space. These have wide 85 outer extensions *o* joined on at such an angle as will allow them to follow approximately the curve of the outer framing or screen *j*, or these outer extensions *o* may be hinged to the wings *f* if desired.

In the case of a two-compartment door 90 which has been folded, I arrange that the whole of the revolving portions are movable to one side, after folding wings *f* upon the central door body *g*, by means of tracks in the form of guide-ways *p* positioned in the 95 roof and floor.

Any or all of the collapsing arrangements 100 described can be brought into action by the movement of one or more levers or other suitable means, mechanically or electrically operable to release them automatically, so as to facilitate the opening of the revolving door in case of panic.

In doors of the two-compartment type it 105 is necessary in order to allow free movement of the surfaces, that actual contact shall not take place between the extended wings *f* and the outer casing *j*, and in order to meet this condition I provide cushions *r* 110 on the outer casing *j*, see Figure 6, which are adjustable as regards projection, in order to give the most effective results in preventing draughts.

The cushions *r* may be in the form of 115 padded strips *s* of wood or other suitable material fitted into upright grooves *t* provided in the outer fixed casing *j*, so that the revolving wings *f* touch them as they come to rest. The cushion can be adjusted by 120 screws *u* operating through the strips *s* and compression springs *v* arranged in connection therewith.

To ensure that the door after use stops 125 correctly in the position shown in Figures 2, 3 and 10 it is necessary to have a mechanical check to stop the revolving motion when the door wings *f* arrive at that point. This checking action is obtained by providing a form of air or oil check that will exert its greatest resistance to the movement of the 130

revolving screens at this point and consequently twice in each complete revolution.

This check works at an angle of forty-five degrees to the axis of the central screen when at rest. The same result may be obtained by a suitably designed mechanical brake which comes into action twice in each revolution of the central door body.

The check device may consist of means having a piston and cylinder z supported on a carriage z' movable by runners z'' on rails z''' . The piston z^a is carried by a rod z^b , slotted to act as a relief pressure valve, and has a runner z^c co-acting with a spring constrained lever z^d pivoted at one end to a member z^e and at the other end the spring z^f is attached. A further lever z^{10} (shown above the member Z^b in Figure 15, but below in Figure 14) is pivoted to the member z^e at one end and at the other end is connected by cable or rope z^g to a counterpose or handle z^h on pulling of which the doors can be turned to a position at right angles to the normal or moved to side of casement. The lever z^{10} has a cam or raised part z^{11} co-acting with a runner z^{12} arranged in connection with a central door pivot z^{13} which turns on ball bearings. At the full line position shown in Fig. 15 the parts are at rest, as when the door is closed, and the dotted position of the lever z^{10} indicates the position this lever takes up when the pull upon the cable or rope z^g is exerted against the resistance of a recoil spring z^{14} the ends of which are anchored to the lever z^{10} and the member z^e in line with the cam z^{11} .

The automatic release of the wings f to cause collapse of the same may be effected through the agency of a key or handle w adapted to operate by exerting a pulling action thereon a cable x to withdraw the bolts holding the wing brackets and the upper and lower door bolts or pivots simultaneously. This cable can be concealed in the door structure and is pulled taut by the key w through which the cable passes. This is shown in Figures 9, 11, 12 and 13. For obtaining this automatic release in doors with radial wings (see also Fig. 16) the wing brackets l are hinged at one end to the central door frame g and are secured at the outer end by spring bolt catches c attached to cables x passing over guide pulleys D and down an opening or hole E provided in the door frame g where they pass and are connected to the top and bottom pivots so as to withdraw the same for the purposes described. The adjustable pivoted brackets l on release of their catches swing down on their hinges and allow the wings f to fold by the action of the springs k .

Revolving doors according to my invention may be made of wood, metal, either separately or combined, or of any suitable materials.

Having now described my invention, what I claim as new and desire to secure by Letters Patent is:—

1. The combination with two oppositely curved casement walls, a framing disposed therebetween, and foldable leaves attached to said framing adapted to open centrally from the closed position, said framing and leaves forming a revolving central door screen, of foldable wings carried by the said framing and revolving with the said screen in an extended position at right angles to the said screen adjustable brackets for holding the said wings in the extended position pivoted to the said framing at one of their ends, and releasable catches provided at the other end of the adjustable brackets, the attachment of said leaves to said framing comprising hinges provided with resilient means for returning the said leaves to the closed position.

2. The combination of two oppositely curved casement walls, a framing disposed therebetween and foldable leaves carried by the said framing, adapted to open centrally said framing and leaves forming a revolving central door screen, foldable wings carried by the said framing and revolving with the said screen, adjustable brackets for holding the said wings in extended position, a pivot to which each adjustable bracket is attached at one end, a releasable catch provided at the other end of the bracket, a spring hinge forming the attachment of each leaf to said framing and adapted to return the leaf to its closed position and releasable spring catches or bolts for holding the leaves in their closed position.

3. The combination of two oppositely curved casement walls, a framing disposed therebetween and capable of revolving, foldable leaves carried by said framing so as to constitute a central door screen, a pivot on which said screen revolves, foldable wings hinged to the said screen framing and revolving with the screen, adjustable brackets for holding said wings in extended position, a pivot to which each adjustable bracket is attached at one end, a releasable catch provided at the other end of the bracket, a spring hinge forming the attachment of each leaf to said framing and adapted to return the leaf to its closed position, and springs interposed between the foldable wings, held in extended position by the adjustable brackets, and the central door screen for folding the said wings upon the central door screen when the spring catches of the adjustable brackets have been withdrawn and the said wings released for folding.

4. The combination of two oppositely curved casement walls, a framing disposed therebetween and foldable leaves carried by the said framing adapted to open centrally said framing and leaves forming a central

door screen, flat foldable wings carried by the said framing and revolving with the said screen, adjustable brackets for holding the said wings in extended position, a pivot to which each of said brackets is attached at one end, a spring controlled releasable catch carried by the other end of the bracket, and a spring hinge forming the attachment of each leaf to said framing and adapted to return it to its closed position.

5. The combination of two oppositely curved casement walls, a framing disposed therebetween and foldable leaves carried by the said framing adapted to open centrally said framing and leaves forming a central door screen, flat foldable wings having canted extensions connected therewith and carried by and revolving with the said screen, adjustable brackets holding the said wings in extended position, a pivot to which each of said brackets is attached at one end, a spring controlled releasable catch at the other end of each bracket and a spring hinge forming the attachment of each leaf to said framing and adapted to return it from open to closed position.

6. The combination of two oppositely curved casement walls, a framing disposed therebetween and foldable leaves carried by the said framing adapted to open centrally said framing and leaves forming a central door screen, foldable wings hinged to said screen framing and revolving with the same, adjustable brackets holding said wings in extended position, a pivot to which each adjustable bracket is attached at one end, a releasable spring-controlled catch at the other end of each bracket, a spring hinge forming the attachment of each leaf to said framing and adapted to return the leaf to a closed position, and adjustable draught excluding cushions, spring exerted, located in a groove at each side of each casement wall and co-acting with the free edges of the extended wings carried by the central door screen to close the air space between the casement and the said edges when the door is in its closed position.

7. The combination of two oppositely curved casement walls, a framing disposed therebetween and foldable leaves carried by the said framing adapted to open centrally said framing and leaves forming a central door screen, foldable wings hinged to said screen framing and revolving therewith, ad-

justable brackets holding said wings in extended position, a pivot to which each adjustable bracket is attached at one end, a releasable spring-controlled catch at the other end of said bracket, cable means operable to release the spring-controlled catches and the adjustable brackets to allow the wings to fold inwardly on the screen, and springs each attached at one end to the screen and at the other to a wing to cause the inward folding movement.

8. The combination of two oppositely curved casement walls, a framing disposed therebetween and foldable leaves carried by the said framing adapted to open centrally said framing and leaves forming a central door screen foldable wings hinged to said screen framing and revolving therewith, adjustable brackets holding said wings in extended position, a pivot to which each adjustable bracket is attached at one end, a releasable spring-controlled catch at the other end of each bracket, cable means operable to release the spring-controlled catches, and the adjustable brackets, springs to cause the wings to fold, and means to operate the cable.

9. The combination of two oppositely curved casement walls, a framing disposed therebetween and foldable leaves carried by the said framing adapted to open centrally said framing and leaves forming a central door screen, foldable wings hinged to said framing and revolving therewith, adjustable brackets holding said wings in extended position, a pivot to which each adjustable bracket is attached at one end, a releasable spring-controlled catch at the other end of each bracket, cable means operable to release the spring-controlled catches and the adjustable brackets, springs to cause the wings to fold, means to operate the cable, lever mechanism connected therewith, a central pivot, on which the door turns co-acting with the said lever mechanism, a piston and cylinder and a piston rod, slotted to act as a pressure relief valve combined therewith operating at an angular position in relation to the axis of the central door screen to check the movement of the latter and to bring it to a state of rest at the closed position of the door.

In testimony whereof I have signed my name to this specification.

CECIL ALEXANDER ELLIOTT.
